US0D1041440S

(12) **United States Design Patent** (10) Patent No.: **US D1,041,440 S**
(45) Date of Patent: ** Sep. 10, 2024

(54) **SOUND AMPLIFIER**

(71) Applicant: **UNITRA SPÓŁKA Z OGRANICZONĄ ODPOWIEDZIALNOŚCIĄ, Warsaw (PL)**

(72) Inventors: **Wiktor Szulfer, Warsaw (PL); Adrian Krupowicz, Warsaw (PL)**

(73) Assignee: **UNITRA SPÓŁKA Z OGRANICZONĄ ODPOWIEDZIALNOŚCIĄ, Warsaw (PL)**

(**) Term: **15 Years**

(21) Appl. No.: **35/515,826**

(22) Filed: **Nov. 16, 2022**

(80) **Hague Agreement Data**

Int. Filing Date: **Nov. 16, 2022**

Int. Reg. No.: **DM/225401**

Int. Reg. Date: **Nov. 16, 2022**

Int. Reg. Pub. Date: **Dec. 23, 2022**

(57) **CLAIM**

The ornamental design for sound amplifier, as shown and described.

DESCRIPTION

1. Sound amplifier

1.1 : Perspective

1.2 : Front

1.3 : Back

1.4 : Bottom

1.5 : Left

1.6 : Left

1.7 : Top

(Continued)

The broken lines shown in the drawings represent unclaimed portions of the article and form no part of the claimed design.
